COOLING MEANS FOR A WIRE DRAWING BLOCK
Carl O. Brustle, Metuchen, N.J., assignor to Syncro
Machine Company, Perth Amboy, N.J., a corporation
of New Jersey

Filed Sept. 20, 1960, Ser. No. 57,318
11 Claims. (Cl. 205—20)

The present invention relates to wire drawing machines and particularly to means for cooling the wire drawing blocks thereof.

More particularly still the invention relates to air cooling means for the wire drawing blocks.

In a copending application Serial No. 38,562 now Patent No. 3,130,832, issued April 28, 1964 I have described a means for directing air streams against the exterior surface of a wire drawing block and the wire thereon. This system is incorporated in the apparatus of the present invention. The prior application, however, showed no means for cooling the interior surface of the block and it was contemplated that the usual water cooling be utilized in combination with the air cooling mentioned. Water cooling, however, while efficient, requires expensive piping and contributes to unpleasant and frequently undesirable operating conditions since, especially in hot weather, the water cooled block acts as a condenser of the surrounding air and causes sweating with attendant loss of soap film from the wire convolutions surrounding the block face. Drawing dies will quickly lose their tolerance and damaged wire surface results due to interruptions of the lubrication film. This frequently occurs during stoppage of the machine.

By utilizing solely air cooling as disclosed in the instant specification these conditions are overcome and, in fact, if the cooling air is refrigerated, the use thereof to cool the wire serves as a by-product to lower the temperature of the plant in which the machines are operating.

It is an object of the invention to provide a wire drawing machine in which the drawing blocks are cooled solely by air.

Another object of the invention is to provide such air cooling means incorporating means to direct air streams on both the internal and external surfaces of the drawing blocks.

It is a further object of the invention to provide such air cooling means wherein the external air streams are directed onto the block from positions closely adjacent thereto and wherein the air is supplied through toroidal channels hingedly mounted to be readily moved away from the drawing blocks during the stringing up of the drawing machine.

Other objects and features of the invention will be apparent when the following description is considered in connection with the annexed drawings, in which,

FIGURE 1 is a fragmentary transverse cross-sectional view through one of the drawing blocks of a wire drawing machine showing one embodiment of my invention wherein air streams are directed on both the interior and exterior of the drawing block;

FIGURE 2 is a fragmentary top plan view of the device of FIGURE 1 showing particularly the mode for hingedly mounting a toroidal air distributing channel in position about a drawing block;

FIGURE 3 is a fragmentary vertical cross-sectional view taken on the plane of the line 3—3 of FIGURE 1 and illustrating the mode of connecting the toroidal air channel to a supply channel;

FIGURE 4 is a horizontal cross-sectional view taken on the plane of the line 4—4 of FIGURE 1 showing particularly the use of ribs on the interior surface of a drawing block to provide additional cooling area to

2

gether with the use of a deflector structure to cause the air stream to flow between and about the ribs and the interior surface of the drawing block;

FIGURE 5 is a transverse cross-sectional view through a drawing block showing a modified form of means for directing air streams against the interior surface of the drawing block, this form including an interior generally toroidal shaped channel having apertures therein for directing air against the inner surface of the drawing block; and

FIGURE 6 is a transverse cross-sectional view through a drawing block showing a further modified form of means for directing air against the interior surface of a drawing block. In this form no structure internal to the drawing block is utilized but instead air is supplied from the external torus and directed against the interior surface of the drawing block

Referring now to the drawings and more particularly to FIGURE 1, there is shown therein the usual base 10 which supports a drawing block 11 driven by means of the shaft 12 in any suitable manner. The drawing block 11 is provided with apertures 13 in its upper surface which, as will later be described, serve to permit air flowing upwardly over the inner surface of the block to escape.

Mounted within the drawing block 11 is a bell shaped structure 14 which seats on the base 10. Adjacent the lower end of the bell 14 and spaced outwardly therefrom is a generally circular vertically extending member 15 the flanged base of which is fixed to the machine base 10.

Drawing block 11 is provided with a downwardly extending rim 16 which lies adjacent an inwardly extending flange 17 on the circular member 15. The members 16 and 17 form a sufficiently airtight seal so that little air entering the toroidal passage formed by the machine base, the member 15, the lower portion of bell 14 and the lower surface of block 11 will be discharged other than upwardly between the upper portion of bell 14 and the inner surface of block 11.

The toroidal channel just above described is joined by means of the duct 18 to a main air duct 20 so that air supplied through duct 20 is directed through the toroidal passageway, designated 21 for convenience, and thence upwardly along the inner surface of block 11 and out through the apertures 13. As will be seen particularly by reference to FIGURES 1 and 4, the interior surface of the block 11 is provided with fins 22 which lie closely adjacent to the outer surface of the bell 14 and thus cause air from the toroidal channel 21 to pass upwardly over the inner surface of the block 11 and over the surfaces of the fins 22 which act as radiators and permit the cooling air to readily remove heat from the inner surface of the block 11.

The drawing blocks are also cooled by air directed against their outer surfaces in a manner similar to that disclosed in my above-identified patent. The hinge means has, however, been considerably simplified.

Referring now to FIGURES 1 through 3, a toroidal structure generally designated 23 is provided, this structure comprising an inner cylindrical member 24, an outer cylindrical member 25 and end rings 26 and 27. On one side of the structure 23 a generally rectangular hollow duct 28 is fixed to the cylinder 25, this duct extending to the right as shown in FIGURE 1 and being fixed to a tube 30 having closed ends 31 serving as hubs and being mounted on a shaft 32 which extends horizontally along the drawing machine at the rear of the drawing blocks. Apertures such as indicated at 33 and 34, FIGURES 1 and 2, are provided in the tube 30 so that air can enter the duct 28 and the toroidal chamber 23. As is clearly seen in FIGURES 1 and 3, the tube 30 protrudes into the

main air duct 20. A rectangular gasket member 34a is provided so that there is no leakage of air between the aperture in duct 20 and the tube 30, this gasket being shown in elevation in FIGURE 3.

Shaft 32 is rotatably mounted in bearings 35 fixed to the vertical wall of air duct 20 and this shaft is provided with an arm 36 (FIG. 2) by means of which all of the toroidal chambers 23 may be pivoted and removed from their position about the respective drawing blocks for purposes of machine stringing up and the like as more specifically set forth in my above-mentioned patent. It will of course be understood that the toroidal structure 23 is notched at two locations to provide for entry of wire to and delivery of wire from the drawing block during normal operation as disclosed in said patent.

As has been indicated above, air flows through the main duct 20 through the tubes 30 and into the toroidal chambers 23. The inner cylindrical walls 24 of the toroidal chambers 23 are provided with apertures 37 which lie closely adjacent the outer surface of the respective drawing blocks. Thus streams of air are directed against the blocks at high velocity the distances being so small that the cooling effect of the rapid expansion of air as it leaves the ducts is effective to cool the blocks.

In a second embodiment of this invention the bell structure 14 is replaced by a similar structure indicated at 40 in FIGURE 5. The structure 40 provides a complete annular chamber within the drawing block 11 and communicates by means of a duct 41 similar to the duct 18 with the main air duct 20. In this embodiment of the invention the projection 16 on the lower end of the drawing block 11 is retained and mates with and rotates in a groove 42 in the horizontal surface 43 of the wall of the annular chamber above mentioned. As indicated above, the annular chamber is formed by the member 40 which seats on the base 10 at 44, extends vertically upwardly, has a reentrant bend 45, thence extends downwardly as indicated at 46, then horizontally as mentioned at 43 and then extends again downwardly seating against the base at 47.

Apertures 48 are formed in the outer wall of the annular chamber 40, that is, in the portion 46 thereof, being closely adjacent to the inner surface of the drawing block 11. Thus air supplied through the ducts 20 and 41 to the annular chamber 40 is discharged at high velocity through the apertures 48 and is extremely effective in cooling the inner surface of the drawing block 11.

The remaining structure of this embodiment of my invention is identical to that described above in connection with FIGURES 1 through 3 and for that reason the description is not here repeated. The parts are, however, designated by the same reference characters.

Referring now to FIGURE 6 there is shown therein a slightly modified form of my invention which does not utilize an air distributing structure within the drawing block but which instead supplies air from the external toroidal structure which passes downwardly to the drawing block and out to thereby cool the block.

In this embodiment of my invention the toroidal chamber 23 of the other figures of the drawing is modified so that it becomes a dome-shaped member 50. Thus the cylindrical walls 24 and 25 as well as the end plate 26 are retained but instead of utilizing the other end ring 27 the top is closed in by the spaced disks 51 and 52 providing a passageway across the top of the drawing block 11.

As before, air which enters through the main duct 20 and duct 28 (previously described) passes through the apertures 37, impinges against the outer wall of the drawing block 11 and flows thence downwardly over the outer surface of the drawing block 11 and out around the edges of the dome-shaped member 50.

Relatively large apertures 53 are provided in the lower disk 52 and therefore air from the chamber 23 flows through these holes and through the apertures 13 in the

block 11 after which this air is discharged downwardly over the inner surface of block 11 passing over the fins 22 and thence out to atmosphere.

While I have described preferred embodiments of my invention, it will be understood that I wish to be limited not by the foregoing description, but solely by the claims granted to me.

What is claimed is:

1. Means for cooling the drawing blocks of wire drawing machines, comprising, in combination, a toroidal member having a cylindrical wall thereof extending generally parallel to and surrounding the exterior surface of each drawing block and of substantially the same axial extent as the drawing block, means for supplying cooling air thereto, apertures in said wall through which said

cooling air flows to impinge on the vertical surface of the drawing block, a generally bell-shaped member fixedly mounted within the drawing block and having vertical portions thereof extending adjacent the interior surface of the drawing block forming a narrow passageway and means for causing cooling air to flow through said passageway between said vertical surface of said bell-shaped member and said interior vertical surface of the drawing block.

2. A device in accordance with claim 1 wherein a toroidal chamber is formed at the base of said bell-shaped member beneath the lower peripheral edge of the drawing block and wherein said toroidal chamber is connected to a source of air supply whereby air is supplied to said narrow passageway and wherein the drawing block is provided with apertures around its upper periphery, said apertures serving to permit egress of air from within the drawing block.

3. A device in accordance with claim 1 wherein the drawing block is provided with inwardly extending fins on its interior periphery, said fins extending adjacent the vertical surface of said bell-shaped member whereby air passes over said fins and cools the interior surface.

4. A device in accordance with claim 1 wherein said toroidal member is in the form of a dome having a hollow top and wherein the lower member of said hollow top has apertures therein whereby air passing through said member is passed downwardly into said narrow passageway between said bell-shaped member and the interior surface of the drawing block to perform a cooling operation.

5. A device in accordance with claim 4 wherein a toroidal chamber is formed at the base of the drawing block, whereby air discharged through said narrow passageway passes into said chamber, said chamber being provided with apertures in the external periphery through which the air passes to the atmosphere.

6. A device in accordance with claim 5 wherein the interior surface of said block adjacent said bell-shaped member is finned to provide additional cooling surface for the block.

7. A device in accordance with claim 6 wherein the wire drawing block is provided with apertures in its upper surface to provide for egress of air discharged against the interior vertical wall of the block through the said apertures.

8. A device in accordance with claim 1 wherein said bell-shaped member is hollow and wherein cooling air is supplied to said hollow bell-shaped member through a duct and wherein said member has apertures in the wall thereof facing the interior of the drawing block whereby cooling air is emitted from said apertures directly on the surface of the drawing block, said air being expanded at a point close to the block to enhance the cooling effect.

9. A device in accordance with claim 1 wherein said toroidal member is hingedly mounted, said mounting comprising a shaft, bearings mounted on an air duct fixed to the base of the machine, said shaft being mounted in said bearings and closed tubular members mounted on said shaft for rotation therewith, said tubular members project-

ing through rectangular openings in the walls of said air duct, said tubular members having substantially diametrically spaced rectangular openings supplying air from said duct to said toroidal member.

10. Means for cooling drawings blocks of a wire drawing machine comprising, an annular air supply chamber extending about the outer peripheral walls of the drawing block and spaced closely adjacent thereto, said chamber having a dome-shaped top comprising outer and inner disk-like walls, said lower wall having a plurality of apertures therein adjacent its periphery, a bell-shaped member within the drawing block having a vertically extending portion positioned closely adjacent to the inner periphery of the drawing block, and a plurality of apertures in the upper surface of the drawing block whereby air supplied from said dome is ejected through said apertures in said lower disk and the drawing block and flows through the passageway between said bell-shaped member and said interior surface of the drawing block to thereby cool the block.

11. Cooling means for the interior surface of a wire drawing block, said means comprising a bell-shaped

member mounted within the wire drawing block said bell-shaped member having a vertically extending portion spaced closely adjacent the corresponding vertically extending portion of the interior surface of the drawing block, said bell-shaped member being hollow, means for supplying air to the hollow interior of said bell-shaped member, apertures in said bell-shaped member through which cooling air is ejected to impinge upon the interior surface of the drawing block and apertures in the upper surface of the drawing block to permit air to escape from the interior of the drawing block.
